UNITED STATES PATENT OFFICE.

JEROME BOGLE AND JOSEPH S. C. SOWAR, OF BRAZIL, INDIANA.

FREIGHT-CAR.

SPECIFICATION forming part of Letters Patent No. 434,057, dated August 12, 1890.

Application filed December 28, 1889. Serial No. 335,242. (No model.)

To all whom it may concern:

Be it known that we, JEROME BOGLE and JOSEPH S. C. SOWAR, citizens of the United States, residing at Brazil, in the county of Clay 5 and State of Indiana, have invented certain new and useful Improvements in Freight-Cars; and we do hereby declare the following to be a full, clear, and exact description of the invention, such as will enable others skilled in 10 the art to which it appertains to make and use the same.

This invention relates to new and useful improvements in freight-cars, particularly those designed for the transportation of soft 15 coal; and it consists in certain improvements on a car for which Letters Patent were granted to us, as assignees, No. 370,720, of date September 27, 1887, "freight-car," the object of our said improvements being to obtain in- 20 creased efficiency with greater simplicity of parts by means of important modifications hereinafter described and claimed.

In the accompanying drawings, which illustrate our invention, Figure 1 is a view of a 25 side of a car having our improvements applied thereto; Fig. 2, a section on line xx , Fig. 1.

This invention being an improvement on our former patent, No. 370,720, we shall limit 30 the description to those features in which the new and useful modifications and improvements have been made, and for which Letters Patent are prayed by this application.

In our present invention the roof of the car 35 is made the same width as the car proper.

The adjustable side or door of the car is constructed of a folding section A, and sliding sections B, hinged thereto. The folding section A is composed of two or more longitudinal boards c, which are connected to each 40 other at suitable intervals by metallic braces j, the lower ends of which may terminate in a loop for the reception of the longitudinal rod I, whereby the sliding sections B are hinged to A. The sliding sections B are 45 doors or gates, preferably formed of longitudinal slats m and suitable bracing-pieces o. These doors are hinged, as aforesaid, to the folding section A by metallic strips p, attached at or near their top, said metallic strips being similar in form and function to

strips j, and having a loop in their upper end whereby they are suspended on the rod I.

k are irons bolted to the upright standards of the car to hold the doors or gates B in position when let down in order to open the car, it being designed that the doors shall slide vertically between the standards, the irons k serving as guide rods or bars.

In order to raise and lower the adjustable 60 side of the car, we employ chains g, which are attached in any convenient manner to the top of the longitudinal folding section A at the ends and at suitable intermediate points thereof, and are passed from thence over pulleys x x, attached to the standards, to spools on the central longitudinal shaft F, as best shown in Fig. 2.

To open the car, the adjustable side is dropped by unwinding the chains from the central pulley-shaft F by a crank. (Not shown.) The doors B slide down readily between the standards, and when down full length, or at their lowest position, the longitudinal section A folds over the same, as shown in Fig. 75 2, where the boards c c of the folding section A are seen in cross-section, and the side of the car is open its entire length and ready to receive its load. Then by merely turning a crank on the shaft F the whole is drawn up 80 into position and the car is closed.

What we claim is—

1. The combination, in a freight-car, of an adjustable side composed of a longitudinal folding section and short sliding doors hinged 85 in a pendent manner thereto, substantially as described.

2. The combination, with the longitudinal folding section, of the sliding doors, the metallic strips j and p, and the rod I, by which 90 the sliding doors are hinged to said section, substantially as described.

3. The combination, in a freight-car, with an adjustable side composed of a longitudinal folding section and short sliding doors hinged 95 in a pendent manner thereto, of guides bolted to the standards to properly guide and hold said sliding doors, substantially as described.

4. The combination, in a freight-car, with an adjustable side composed of a longitudinal 100 folding section and short sliding doors hinged in a pendent manner thereto, of chains secured

at their upper ends to spools on the main pulley-shaft and at their lower ends to the folding side, and pulleys attached at or near the top of the standards and traveled by said chains, substantially as described.

5. The combination, in a freight-car, with an adjustable side composed of a longitudinal folding section and short sliding doors hinged in a pendent manner thereto, of guides bolted 10 to the standards to properly guide and hold said sliding doors, chains secured at their upper ends to spools on the main pulley-shaft

and at their lower ends to the folding side, and pulleys attached at or near the top of the standards and traveled by said chains, substantially as described. 15

In testimony whereof we affix our signatures in presence of two witnesses.

JEROME BOGLE.
JOSEPH S. C. SOWAR.
